UNITED STATES PATENT OFFICE.

GLENN L. JACKSON, OF CHICAGO, ILLINOIS.

BOOKMARK.

Application filed September 8, 1924. Serial No. 736,407.

My invention relates to book-marks and more particularly to a device of this type which is simple, effective, easily used, and cheap to manufacture.

Heretofore, devices of the prior art have been of complicated design. These devices are made bulky and awkward, and are expensive. It is common for them to have unsightly and undesirable projections extending beyond the margin whereby these projections are liable to be knocked in the handling of the book which usually results in the losing of the book marks, or their places in the book or injury to the book. Furthermore, they are usually of paper, or other thick material, which makes them less practical and useful.

An object of my invention is to provide a book-mark of improved design, which overcomes the above objections, and is practical and capable of extensive use.

Other objects and advantages will appear from the following detailed description taken in connection with the accompanying drawing, in which:

Figure 1 illustrates a plurality of book-marks in use along the margin of the leaves of a book;

Fig. 2 illustrates, on a larger scale, one of the book-marks as applied to the margin of a leaf;

Fig. 3 is a plan view of the device before finally formed;

Fig. 4 is a top view of the device; and

Fig. 5 is a side view of the same.

Referring now to the drawings, a book-mark embodying my invention comprises a strip 1 of relatively thin flexible tenuous sheet material, such as metal, or other suitable material, bent across in a straight line near the middle, or between its ends, so as to provide flatly opposed legs 2 and 3 preferably of different lengths. Legs 2 and 3 may be resiliently, but lightly, pressed against each other, so that a leaf may be easily inserted, yet gripped by sufficient pressure to prevent the book-mark from accidentally slipping off. I find that, if I employ sheet metal of considerable thinness, it is possible to stamp out the strip 1 shown in Fig. 3 and quickly bend it to the form shown in Fig. 5. In this latter figure it is apparent that both legs may be brought so closely together that practically no space is left at the point designated 5, but in view of the

fact that the material is thin and flexible, the legs 2 and 3 quickly spread when a leaf of the book is inserted.

However, it will be noticed that the minimum separation of the legs is adjacent to the edge 6, so that the leaf will be gripped the greatest when the book-mark is moved inward the full length, that is, the maximum gripping effect of the legs 2 and 3 upon the leaf inserted therebetween will be at the edge 6, or in close proximity thereto, thereby requiring the book mark to be mounted the maximum length which allows only the edge 6 to protrude. The margin of the leaf will contact with the edge 6 and be strengthened thereby at this place. This tends to prevent the leaf from being torn when the book is opened to locate the place marked by the device, the leaf sometimes being gripped at the spot to turn the remaining leaves forwardly or backwardly as the case may be.

Leg 2 may be the upper leg. If so desired it may be formed to serve as a pointer, the purpose of which allows the book mark to be placed anywhere along the margin of the leaf to designate the place last read by the person. It is at this point in the description that I desire to emphasize the versatile use of my device. Its simple construction permits its mounting anywhere along the margin of the leaf to indicate that part of the page, as well as the page itself, last read. I find that merely marking the page is insufficient in itself, as it generally requires considerable re-reading, or loss of time to find particular data which has been noted for future use.

In use, the device is slipped upon the leaf, this being facilitated by the lower leg 3 being the longer leg, and also by a notch 4 provided therein. The device is of a thin strip of light metal and bent near the middle so that nothing but the edge 6 lies outside the book, but this edge is thin and lies closely against the margin of the leaf, in a straight line and in contacting relation (as illustrated in Fig. 2), which is just sufficient to indicate the location of the device when in position on a leaf of a book when closed. Hence, the device fully and effectively serves its purpose, without being too complicated, bulky, unsightly, or so heavy as to tear the leaf of a book.

In Fig. 2, I have shown my device enlarged

and placed upon a leaf of a book primarily to illustrate the relative thickness of the legs of the book-mark with respect to the thickness of the page, and also the manner in which these legs lie flatly against the opposite sides of the leaf.

While not illustrated, the device may be furnished with the legs 2 and 3 pinched tightly against each other. In view of the resiliency of the sheet material employed, the legs may be readily separated, when the device is used, merely by placing the longer leg on one side of the leaf and pressing it thereagainst, whereupon both legs spread, the same as shown in Fig. 5. In either event, the book-mark lies closely against the leaf on opposite sides, as shown in Fig. 2, and eliminates any bulging of the book when closed.

20 By my invention I avoid all undesirable projections from the margin of the leaf and provide the thin edge 6 only lying without the leaf, which edge provides a neat appearance, and holds the device on the leaf, and at the same time serves to indicate the location of the book-mark.

It will be observed that my book-mark in its preferred form, as disclosed in the specification, is made from one piece and kind of metal or other resilient material without the use of glue or adhesive substance whatever. The cost of manufacture is thereby reduced to a minimum and the possibility of different members becoming detached from each other is obviated. The device can be attached to a page and removed innumerable times without damage to it or to the page. It does not project from the edge of the book page more than the thickness of the material, which is about the thickness of a sheet of paper. It can, therefore, be used on books that are carried in brief cases or in the pocket and will not be subject to accidental removal or displacement, nor be the cause of damage to the book. It is designed and adapted to be removably attached to the book-leaf in a manner and at a place that will indicate to the reader the exact line to start reading. Being made of one integral piece bent intermediate of its ends to form two opposed holding or gripping members, the gripping or holding effect of the device on the leaf of a book arises from a balanced and equal pressure upon directly opposite sides of the leaf and, accordingly, there is no tendency of the device either to tear or shear the book-leaf at the edges of the tongues or members, or to bend or crush the leaf around the tongues. Moreover, the holding power of these tongues comes from the bend in the metal and the full width of the metal is utilized in this bend, so that the metal may be practically as thin as the book-leaf and the device will yet hold securely. Thus

without projecting beyond the edge of the leaf more than the thickness of the metal a substantial and secure gripping device is secured. By making the device in this way, thin material may be used while at the same time securing strength and a firm grip on the book-leaf.

Again, my device depends for its support upon the leaf only to which it is applied and is not required to be attached to the cover of the book which would be objectionable for various reasons, such as the difficulty of making it applicable alike to thick and thin books and the liability to displacement when the books are pushed into or removed from a closely packed line of books on a library shelf. It is intended to mark the place last read or where next to begin reading after the book has been laid away or placed on the shelf as in libraries. In the latter case, the presence of the device in the book is not noticeable; it is not liable to displacement in the handling of the book in returning it to the shelves or getting it again for the reader, and the book is not injured by tearing, shearing or creasing of the leaves.

I claim:

1. A book mark adapted to be slipped over the edge of a leaf of a book consisting of a narrow strip of light flexible tenuous sheet material sharply bent across in a straight line to form flatly opposed legs, said legs being spaced apart a distance less than the thickness of the leaf at a point in close proximity to the bend whereby the device lightly and flexibly grips the edge of the leaf, thereby affording minimum separation of the leaves of the book when closed, and also requiring the device to be slipped the maximum distance inwardly on the leaf, said bend lying in a close straight line contact against the edge of the leaf so as to afford a protrusion from the leaf no greater than the thickness of the material.

2. A book mark adapted to be slipped over the edge of a leaf of a book consisting of a narrow strip of light, flexible, tenuous sheet-material, sharply bent across in a straight line to form flatly opposed legs to embrace the leaf, the sharp bending causing the legs lightly and flexibly to grip the extreme edge of the leaf and affording minimum separation of the leaves of the book when closed, and the straight bend enabling the device to be placed at any point along the edge of the leaf without objectionably protruding.

3. A book mark adapted to be slipped over the edge of a leaf of a book consisting of a narrow strip of light flexible tenuous sheet material sharply bent across in a straight line to form flatly opposed legs, one of which is shorter than the other and one of which is so formed as to serve as a pointer, said legs lightly and flexibly gripping the ex-

treme edge of the leaf and affording minimum separation of the leaves of the book when closed, the straight bend adapted to lie at any point along the edge of the leaf in close contactual relation so as to afford a protrusion from the leaf no greater than the thickness of the material.

4. A book mark comprising a strip of relatively thin flexible material with a thickness substantially no greater than the thickness of a leaf of a book, said strip being bent to embrace the margin of the leaf and be adjustable there along, said bent portion lying without the leaf and in close contactual relation with its edge whereby this bent

portion protrudes a distance no greater than the thickness of the material.

5. A book mark comprising a strip of relatively thin flexible material bent upon itself between its ends, said strip embracing the margin of a leaf of a book and adjustable there along to indicate any place on the page last read, the bent portion of said strip contacting with the edge of the leaf whereby the protrusion therefrom from the leaf is substantially equal to the thickness of the material.

In witness whereof, I have hereunto subscribed my name.

GLENN L. JACKSON.
